REACTION OF HYDROCARBONS

Melvin M. Holm, San Francisco, Eugene H. Oakley, El Cerrito, and Robert L. Humphreys, El Segundo, Calif., assignors to Standard Oil Company of California, San Francisco, Calif., a corporation of Delaware.

Application October 12, 1940, Serial No. 360,874

8 Claims. (Cl. 196—10)

This invention relates to an improved process for the manufacture of high antiknock motor fuel hydrocarbons by the reaction of paraffinic hydrocarbons with olefinic hydrocarbons in the presence of a sulfuric acid catalyst.

This application is a continuation-in-part of our copending application Serial No. 281,168 filed June 26, 1939, now Patent No. 2,224,102.

It is known that isoparaffinic hydrocarbons can be reacted with olefinic hydrocarbons to produce isoparaffinic hydrocarbons predominating in compounds having a number of carbon atoms equal to the sum of the carbon atoms in the reacting isoparaffin and olefin molecules. For example, the alkylation of isobutane with a butene to make a product rich in isoctane by contact and vigorous agitation with a strong sulfuric acid catalyst is now an established commercial process. The product of such alkylation reactions will be referred to herein as an "alkymer."

In the application of this general alkylation reaction to the manufacture of motor fuel from the isoparaffins and olefins of low molecular weight, especially in the manufacture of aviation gasoline from the normally gaseous isoparaffins and olefins, it is necessary that the product meet certain rigorous standards as to quality, such as those relating to antiknock value, bromine number, gravity and boiling range. Due, however, to numerous difficulties and to the large number of unsuspected variables encountered in the operation of an alkylation process for the production of good quality alkymer motor fuel, it has heretofore been impossible to obtain a product having as high a quality as desired.

In our copending application, Serial No. 281,168, we have disclosed that by keeping the concentration of alkyl acid sulfate in the sulfuric acid catalyst at a low value, which is always below 2% by weight of the acid and usually is substantially below 1%, larger yields of alkymer products boiling in the range of aviation motor fuels are produced and the product has a lower bromine number and a higher antiknock value than when higher concentrations of alkyl acid sulfate are permitted to build up in the catalyst. It was also disclosed that the desired low concentration of alkyl acid ester may be maintained by controlling the rate of addition of fresh acid to the process, by controlling the feed rate and the composition of the charge to be alkylated and thereby the ratio of olefin to sulfuric acid and of isoparaffin to olefin, by controlling the degree of contacting of the hydrocarbon reaction mixture with the acid cata-

lyst or by controlling any number or all of these factors together.

We have now discovered how to further improve the process and the quality of the resulting alkylmer product by the careful coordination and correlation of these and additional features of operation which are especially effective in controlling the alkyl acid sulfate concentration in the sulfuric acid catalyst.

It is one object of the present invention to manufacture isoparaffinic motor fuel hydrocarbons having a high antiknock value.

It is another object of this invention to provide a new and improved process for the alkylation of isoparaffins with olefins to produce saturated high antiknock motor fuel hydrocarbons.

Still another object of this invention is to provide a new and improved process for the alkylation of isoparaffins with olefins to produce saturated high antiknock motor fuel hydrocarbons, the product of which process contains a high proportion of such hydrocarbons boiling in the range of aviation gasoline.

Another object of this invention is to provide a new and improved process for the alkylation of isoparaffins with olefins to produce an alkymer product having a low bromine number and a high A. P. I. gravity.

Still another object of our invention is to provide an improved process for the alkylation of isobutane with butene by means of a sulfuric acid catalyst to produce a substantially saturated alkylmer product of the highest antiknock value yet obtained boiling substantially entirely in the range of aviation gasoline.

Other and further important objects of this invention will become apparent from the following description and the appended claims.

In one method of effecting the alkylation of isoparaffins with olefins by means of a sulfuric acid catalyst the olefin or olefins and the isoparaffin or isoparaffins to be alkylated are continuously mixed with the sulfuric acid catalyst at a relatively low temperature, usually below 150° F., and under sufficient pressure to maintain the reactants in liquid phase. This mixture is agitated to assist in obtaining contact between the acid catalyst and the hydrocarbon reactants and thus to assist in effecting the alkylation reaction.

The mixture is then passed to a separating zone wherein the sulfuric acid catalyst is separated from the hydrocarbon phase comprising unused reactants and products.

The absorption of an olefin of low molecular weight by strong sulfuric acid is a substantially

instantaneous reaction while the alkylation of an isoparaffin by an olefin, at least under conditions hitherto disclosed, appears to be a relatively slow reaction and consequently the concentration of alkyl acid sulfate in the sulfuric acid catalyst will have a tendency to increase unless special precautions are taken to prevent it. However, irrespective of the theoretical explanation of why the alkyl sulfate concentration tends to increase, we have found that certain undesirable results, such as low yields of aviation gasoline fraction and relatively low antiknock value of the alkymer product, are associated with too high concentrations of alkyl acid sulfate in the acid catalyst and we have now discovered a new and effective process for isoparaffin alkylation in which novel means are employed for eliminating these difficulties and whereby an improved alkymer product, of higher aviation gasoline content, higher antiknock value and higher degree of saturation is produced.

The process of this invention contemplates the alkylation of isoparaffins with olefins by intimately contacting them, preferably in liquid phase, with sulfuric acid of alkylation strength and controlling the alkyl acid sulfate concentration in the sulfuric acid at a low value and always below certain critical concentrations, so that the maximum production of alkymers of the highest possible quality may be obtained, by regulating and coordinating the composition of the reaction mixture.

According to one embodiment of our invention the concentration of alkyl acid sulfate, resulting from the reaction of sulfuric acid and olefin, is maintained below certain critical values, which are related to the quality of the product, and especially the antiknock value, bromine number and content of aviation gasoline fractions in the product. The concentration of alkyl acid sulfate in the sulfuric acid catalyst is maintained continually below about 2% by weight of the acid for all temperatures of operation and below about 1% by weight of the acid for temperatures of operation above about 40° F. Even when the temperature of operation is maintained below 40° F. it is preferable, in order to realize the maximum utility of the sulfuric acid as an alkylation catalyst and to produce alkymers of the highest quality, that the concentration of the alkyl acid sulfate be maintained always below about 1% by weight of the acid. This is effected by maintaining in the reaction mixture a high concentration of isoparaffin, a high ratio of isoparaffin to olefin, a high relative proportion of acid catalyst in the reaction mixture at the point of its initial contact with the olefin and the highest practical degree of contact between the hydrocarbon and acid catalyst phases.

We have found that when the composition of the reaction mixture is so controlled and maintained within the limits presently to be discussed an alkymer product may be produced which boils substantially 100% within the range of aviation gasoline, has a bromine number substantially less than 1.0 and has an octane number usually between about 96 and 97.5 by the research motor method, whereas the product produced under conditions not particularly designed to maintain a low alkyl sulfate concentration may contain a maximum of 85 to 90% of aviation gasoline having an octane number of about 92 to 93.

While it is customary in effecting the alkylation of an isoparaffin with an olefin by means of a sulfuric acid catalyst to maintain a molecular excess of the isoparaffin over the olefin in the reac-

tion mixture, which has sometimes been as high as 10 to 1, we have found that by maintaining a ratio of isoparaffin to olefin always above about 50 to 1 and preferably well above 100 to 1, as for instance in the range between 100 and 700 to 1 or even higher at the point of initial contact between the olefin and the acid catalyst and at the same time maintaining the concentration of the isoparaffin to be alkylated in the hydrocarbon phase of the reaction mixture always above 50% and usually above about 60% by liquid volume while effecting a high degree of mechanical agitation and thus producing a maximum surface of contact between the hydrocarbon and acid catalyst phases by means of an efficient mechanical contactor, an alkymer product of high antiknock value, above 95 octane number, and high aviation gasoline content, usually 99% or better, may be produced.

This invention may be better understood by reference to the accompanying drawing wherein one specific embodiment exemplifying the invention is shown in the figure. In this embodiment a mixture of normally gaseous hydrocarbons containing an isoparaffin to be alkylated and the olefin for effecting the alkylation may be introduced through line 1 while the catalyst, sulfuric acid usually of about 96% to 98% H₂SO₄, is introduced through line 2. The mixture of catalyst, 25 olefin and isoparaffin is rapidly passed through line 3 to a mixing or agitating device 4, which may be a centrifugal pump, turbo-mixer, etc. operated at high speed or other appropriate device for effecting a high degree of contact between the hydrocarbon phase and the acid catalyst phase. In this mixing pump the acid catalyst and the hydrocarbon phase, including the olefin and isoparaffin reactants, are thoroughly mixed to give the largest practical surface of contact and thus to effect the alkylation reaction quickly and efficiently and then the resulting mixture discharged through line 5 into a separator 6 in which the sulfuric acid catalyst may be separated from the hydrocarbon phase by gravity.

From the separator 6 hydrocarbons and any unseparated sulfuric acid catalyst withdrawn through line 7, controlled by valve 20, may be passed into a neutralizer 8 in which the hydrocarbons are contacted with a neutralizing agent, such as a caustic alkaline material or the like, introduced into 8 through line 9, to remove the acid and acid reacting bodies, such as alkyl esters present in the hydrocarbon phase. Used caustic solution which has settled in neutralizer 8 may be withdrawn through line 10 or may be recirculated by pump 11 through lines 12 and 9. From the neutralizer 8 the hydrocarbons may be passed through line 17 to a settling tower 13 where the used alkaline solution settles out from the hydrocarbons and is withdrawn through line 14 or may be recirculated to the neutralizer 8 by pump 15 through lines 16 and 9. Fresh caustic may be added when required through line 17 communicating with lines 16 and 9.

Some of the hydrocarbon phase withdrawn from the separator 6 through line 7 may be passed into line 18, controlled by valve 19 and recirculated through the mixer 4 and the separator 6. These hydrocarbons will include some of the alkymer product and a substantial quantity of unreacted isoparaffin which will materially assist in maintaining the high ratio of isoparaffin to olefin and the high concentration of isoparaffin in the hydrocarbon phase in the zone of active

alkylation which, as pointed out above, constitute essential features of the present invention.

Used acid may be removed from the lower part of separator 6 through line 21 and discharged from the system through valve 22 or recirculated through line 2, controlled by valve 23. Fresh acid to replace that which is discharged from the system may be added through line 24, controlled by valve 49, which communicates with line 2.

Instead of operating the separator 6 so as to effect the substantially complete separation of acid and hydrocarbons and then recycling the separated acid and hydrocarbons, as just described, it is frequently found preferable to pass the reaction mixture through the separator 6 at such a rate that while a very substantial amount of coalescence is effected, no continuous acid phase is ever actually separated therein and the recycle stream returned through valve 23 and line 2 to the initial alkylation zone in mixing pump 4 is thus composed of both acid and hydrocarbons.

When, due to the more rapid passage of the reaction mixture as just described or for other reasons, the stream passing from the separator 6 through line 7 contains any considerable quantity of acid it may be sent through line 50, controlled by valve 51 to an auxiliary separating zone 52 in which a final separation of acid from hydrocarbon is effected. From zone 52 the separated acid may be returned through line 53 and valve 54 to line 21 while substantially acid-free hydrocarbon is passed through line 55 and valve 56 to line 7 and neutralizer 8, or if the acid separation has been adequate the neutralizer system 8-13 may be by-passed through line 57 and valve 58 and the hydrocarbon led directly to line 25 and stabilizer 26.

Hydrocarbons, which include the alkymers and unreacted normally gaseous hydrocarbons, may be removed from the upper part of settler 13 or from line 57 through line 25 and passed to an alkymer stabilizer 26 which contains heating coil 27 or equivalent heating means. If the olefinic or isoparaffinic charge to the system contains normal paraffins, a mixture of normal and isoparaffin, such as normal and isobutane, may be removed from the stabilizer 26 overhead through line 28, condensed in condenser 29 and collected in receiver 30. Some of the condensate in receiver 30 may be returned to the upper part of stabilizer 26 through line 31 in order to provide adequate reflux liquid. On the other hand, should the hydrocarbons charged to the system contain no normal paraffin, such as normal butane, the unreacted isoparaffin, such as isobutane, may be passed directly from the stabilizer 26 through line 32, controlled by valve 33 and returned to the mixing zone through line 1. Alternatively, the mixture of normal and isoparaffin may be passed directly to mixer 4 through lines 32 and 3 if desired. The material being returned through line 32 may be liquefied when necessary by any known means, such as a condenser or compressor not shown in the drawing. The alkymer product may be withdrawn from stabilizer 26 through line 34, controlled by valve 35 and passed into a still 36 where the alkymer product may be distilled into any desired cuts, such as an aviation gasoline cut and a bottoms cut.

When the hydrocarbon charged to the system through line 1 is, as is frequently the case, a usual fraction from a cracking reaction, such as the C₄ or butane-butene cut, it will contain nor-

mal and isobutane in a ratio of about three to one and about 45% of normal and isobutenes also in the ratio of roughly three to one. It will thus be readily seen that the hydrocarbon phase of the reaction mixture in the zone of active alkylation in pump 4 and immediately thereafter would contain, after the substantially instantaneous and complete absorption of the olefins by the sulfuric acid, a several fold excess of hydrocarbons other than isobutane unless precautions were taken to prevent it. Due to the recirculation of normal butane and alkymer products through lines 2 and 18, as above described, the concentration of isobutane in the reaction mixture would thus quickly be reduced to a very low value. We have discovered, however, and it is an essential feature of the present invention, that in order to maintain the desired low concentration of alkyl acid sulfate in the sulfuric acid catalyst and thereby to produce an alkymer product of the highest possible quality, the concentration of isobutane in the hydrocarbon phase in the zone of active alkylation must be maintained in excess of 50% and preferably in excess of about 60%. This condition may be realized by charging auxiliary isobutane through line 46 and by separating the mixture of isobutane and normal butane, collected in receiver 30 by passing it through line 37 to an isoparaffin still 38 from which normal paraffin is removed as bottoms through line 39 and isoparaffin is taken off overhead through line 40, condensed in cooler 41 and collected in receiver 42, and returning a portion of the isoparaffin from receiver 42 to the mixing zone through lines 44 and 32. Isoparaffin withdrawn from receiver 42 may be returned to still 38 as reflux through valve controlled line 43, or withdrawn through valve controlled line 45, as desired.

The amount of recirculation of reaction mixture through lines 2 and 18 and the amount of recirculation of isobutane through line 32 necessary to maintain a minimum concentration of isobutane above about 50% in the hydrocarbon phase will, of course, depend to a large extent upon the composition of the feed entering through lines 1 and 46. When this feed contains no normal butane the amount of recirculation may obviously be materially less than when the relatively high proportion of normal butane ordinarily contained in the C₄ cut produced in the cracking operation is present.

It might at first glance appear that by keeping the ratio of isoparaffin to olefin at the high ratio, of above 50 to 1, as in one feature of the present invention the high isoparaffin concentration constituting the other essential feature of the invention would be automatically fixed. The two quantities are, however, entirely independent and both require to be adjusted in order to produce anything like the highest quality alkymer product from a given reaction. This may be illustrated by the following two hypothetical reaction mixtures, I and II:

	I	II
Isobutane	30.0	70.0
Butenes	0.3	0.7
n-Butane	59.7	19.3
Alkymers	10.0	10.0
	100.0	100.0

The isoparaffin to olefin ratio is 100 to 1 in both, while the concentration of isoparaffin is 30% and

70%, respectively. When submitted to the same conditions of alkylation the aviation gasoline fractions (initial boiling point about 85° F. and 90% off at 275° F.) produced from raw materials of these compositions might be expected to be of the order of 93.0 and 96.1 octane number, respectively. This point is further illustrated by the following two examples from actual plant operation.

	Example 1	Example 2
Run number		
Reaction temperature, °F.	5	63
Isoparaffin/olefin in charge	4.3	45
Isoparaffin/olefin at mix point	249	11.4
Isoparaffin concentration in hydrocarbon phase, percent	29.6	15
Volume percent of H ₂ SO ₄ catalyst at mix point	47	70.4
Bé. gravity of acid maintained above degrees	64.7	58.0
Yield alkymers (percent by weight of olefins charged)	153	20
Aviation gasoline in product	100	100
Aviation gasoline octane number	92.8	96.6

Although the alkylation reaction of the present invention may be effected with the isoparaffins and olefins in the gas phase, it is preferred to operate with these reactants in the liquid phase. The sulfuric acid used may be of any concentration known to effect the alkylation reaction, though it is preferred to use sulfuric acid of a concentration between about 95 and about 98% H₂SO₄. The temperature of the reaction may be any temperature known for the alkylation of an isoparaffin by an olefin with sulfuric acid as the catalyst, though it is preferred to operate between 15° F. and 150° F. While the process of our invention may be used to effect the alkylation of any isoparaffin with any olefin known to be capable of such reaction, it is especially suitable for the alkylation of normally gaseous isoparaffins with normally gaseous olefins, such as are usually present in gases obtained from the cracking of petroleum, for example the alkylation of isobutane or isopentane with propylene or any of the butenes.

It will be understood that whenever reference is made herein to the ratio of isoparaffin to olefin it is intended to mean the molecular ratio of light isoparaffin, such as isobutane, to be alkylated to olefin capable of effecting the alkylation, such as normal butene or its equivalent in polybutene. It is also to be understood that whenever the concentration of isoparaffin in the hydrocarbon phase is mentioned it is intended to mean the percentage isoparaffin by liquid volume of the total hydrocarbon in the reaction mixture even though a portion or all of the hydrocarbon may actually exist in the vapor phase.

Having thus disclosed and described our invention which comprises the alkylation of isoparaffins with olefins by means of a sulfuric acid catalyst in which the concentration of alkyl acid sulfate is maintained at a low value by maintaining the ratio of isoparaffin to olefin at the point of initial contact between the olefin and acid above a ratio of about 50 to 1 and the concentration of isoparaffin in the hydrocarbon phase in the alkylation zone above about 50% and preferably above 60% by liquid volume and submitting the reaction mixture to vigorous mechanical agitation in order to provide a maximum surface of reaction between the hydrocarbon and the acid catalyst phases, we claim as our invention:

1. Process of manufacturing high anti-knock

motor fuel constituents boiling in the aviation gasoline boiling range from cracking still gases containing a mixture of isoparaffin, normal paraffin, and olefin, which comprises charging said gaseous mixture to a reaction zone wherein isoparaffin is alkylated with olefin by contact with an alkylation catalyst comprising sulfuric acid of alkylation concentration, simultaneously maintaining the concentration of isoparaffin to be alkylated in the hydrocarbon phase of said reaction zone above 60% by liquid volume of the hydrocarbons, maintaining the ratio of isoparaffin to olefin at the point where the olefin initially contacts the catalyst above 100 to 1, and maintaining a high degree of contact between the acid and hydrocarbon phases to produce a high yield of high anti-knock motor fuel hydrocarbons boiling in the aviation gasoline boiling range.

2. Process of manufacturing high anti-knock motor fuel constituents boiling in the aviation gasoline boiling range from isobutane and butene which comprises alkyling isobutane with butene by contact with an alkylation catalyst comprising sulfuric acid of alkylation concentration, simultaneously maintaining the concentration of isobutane in the hydrocarbon phase in said reaction zone above 60% by liquid volume of the hydrocarbons, maintaining the ratio of isobutane to butene at the point where the butene initially contacts the acid catalyst above 100 to 1, and maintaining a high degree of contact between the acid and hydrocarbon phases to produce a high yield of high anti-knock motor fuel hydrocarbons boiling in the aviation gasoline boiling range.

3. The improvement in the process of alkylating isoparaffins with olefins by means of an alkylation catalyst comprising sulfuric acid of alkylation concentration which comprises maintaining the alkyl acid sulfate concentration in the catalyst sufficiently low to produce a high quality product by effecting a sufficiently high degree of mixing of hydrocarbon and acid catalyst phases thus producing a sufficiently large surface of contact between said hydrocarbon and acid catalyst phases while simultaneously maintaining the molecular ratio of isoparaffin to be alkylated to olefin at the point where olefin initially contacts the acid catalyst above 100 to 1 and maintaining the concentration of the isoparaffin to be alkylated in the hydrocarbon phase of the reaction mixture above 60% by liquid volume of the hydrocarbons.

4. The improvement in the process of alkylating isobutane with butene by means of an alkylation catalyst comprising sulfuric acid of alkylation concentration which comprises maintaining the butyl acid sulphate concentration in the catalyst sufficiently low to produce a high quality product by effecting a sufficiently high degree of mechanical agitation of hydrocarbon and acid catalyst phases thus producing a sufficiently large surface of contact between said hydrocarbon and acid catalyst phases while simultaneously maintaining the molecular ratio of isobutane to butene at the point where butene initially contacts the acid catalyst above 100 to 1 and maintaining the concentration of the isobutane in the hydrocarbon phase of the reaction mixture above 60% by liquid volume of the hydrocarbons.

5. The improvement in the process of alkylating isoparaffins with olefins by means of an alkylation catalyst comprising sulfuric acid of alkylation concentration which comprises maintaining the alkyl acid sulfate concentration in the

catalyst below about 2% to produce a high quality product by effecting a sufficiently high degree of mixing of hydrocarbon and acid catalyst phases thus producing a sufficiently large surface of contact between said hydrocarbon and acid catalyst phases while simultaneously maintaining the molecular ratio of isoparaffin to be alkylated to olefin at the point where olefin initially contacts the acid catalyst above 100 to 1 and maintaining the concentration of the isoparaffin to be alkylated in the hydrocarbon phase of the reaction mixture above 60% by liquid volume of the hydrocarbons.

6. The improvement in the process of alkylating isobutane with butene by means of an alkylating catalyst comprising sulfuric acid of alkylating concentration which comprises maintaining the butyl acid sulfate concentration in the catalyst below about 1% to produce a high quality product by effecting a sufficiently high degree of mechanical agitation of hydrocarbon and acid catalyst phases thus producing a sufficiently

large surface of contact between said hydrocarbon and acid catalyst phases while simultaneously maintaining the molecular ratio of isobutane to butene at the point where butene initially contacts the acid catalyst between 100 to 1 and 700 to 1, and maintaining the concentration of the isobutane in the hydrocarbon phase of the reaction mixture above 60% by liquid volume of the hydrocarbons.

7. Process as defined in claim 2 in which the concentration of isobutane in the hydrocarbon phase in said reaction zone is maintained about 70% by liquid volume of the hydrocarbons.

8. Process as defined in claim 3 in which the concentration of the isoparaffin to be alkylated in the hydrocarbon phase of the reaction mixture is maintained about 70% by liquid volume of the hydrocarbons.
